UNITED STATES PATENT OFFICE.

NISHAN M. BOYAJIAN, OF NEW YORK, N. Y.

CIGARETTE OR CIGAR HOLDER.

1,254,307.

Specification of Letters Patent. Patented Jan. 22, 1918.

Application filed February 19, 1917. Serial No. 149,506.

To all whom it may concern:

Be it known that I, NISHAN M. BOYAJIAN, a citizen of the United States, and a resident of the city of New York, borough of Manhattan, in the county and State of New York, have invented a new and Improved Cigarette or Cigar Holder, of which the following is a full, clear, and exact description.

This invention relates to a holder for 10 cigars or cigarettes and it has for its general objects to provide a holder of comparatively simple and inexpensive construction, reliable and efficient in use, and so designed that the nicotin or tobacco is effectively prevented from reaching the smoker's lips or 15 tongue; the cigarette or cigar stub can be easily removed, and at the same time discoloring of the smoker's fingers from nicotin is prevented.

20 A more specific object of the invention is the provision of a tubular holder which has spaced internal flanges which do not interfere with the draft during the inhaling, but which arrest the passage of nicotin to the 25 smoker's lips or mouth, and one of the flanges serves as an abutment or seat against which the cigar or cigarette bears to limit its insertion into the holder, the tubular body of the holder being slotted at opposite 30 sides so as to form gripping jaws and also to expose the stub or butt of the cigar or cigarette, so that it can be gripped by the finger and thumb for easy removal.

With such objects in view, and others 35 which will appear as the description proceeds, the invention comprises various novel features of construction and arrangement of parts which will be set forth with particularity in the following description and claim 40 appended hereto.

In the accompanying drawing, which illustrates certain embodiments of the invention and wherein similar characters of reference indicate corresponding parts in all the views,

45 Figure 1 is a perspective view of the invention as a cigarette holder, showing a cigarette therein;

Fig. 2 is a horizontal section of the holder;

Fig. 3 is a side view of Fig. 1;

50 Fig. 4 is an end view;

Fig. 5 is a modification showing recesses whereby the holder can be gripped between the smoker's teeth;

Fig. 6 is a longitudinal section of the form shown in Fig. 5;

55

Fig. 7 is a longitudinal section of a cigarette holder made from circular tubing;

Fig. 8 is an end view thereof;

Fig. 9 is a perspective view of the holder designed for a cigar;

60

Fig. 10 is a longitudinal section of the form shown in Fig. 9;

Fig. 11 is a side view of a cigar holder with one of the jaws hinged; and

Fig. 12 is a longitudinal section of Fig. 11.

65

Referring to Figs. 1 to 4 inclusive, the cigarette holder A is made of a metal or other material of oval cross-section so as to fit a correspondingly shaped cigarette B. The holder A has spaced internal flanges 1 and 2 which coöperate to form a chamber 3 in which the nicotin collects. The flange 2 serves as an abutment for receiving the tip end 4 of the cigarette B. This cigarette-receiving end is provided at opposite points 75 with longitudinal slots 5 whereby gripping jaws 6 and 7 are formed. The cigarette is inserted between the jaws and bears against the flange 2, and in this manner the cigarette is firmly held and a tight joint is provided between the holder and cigarette.

In Figs. 5 and 6 the tubular holder has indentations or recesses 8 at opposite sides to enable the teeth to more firmly grip the holder. In Figs. 7 and 8 the cigarette holder 85 is constructed in the same manner as in Figs. 1 and 2, with the exception that the tubular body A' is of circular cross-section.

In adapting the invention to a cigar the holder A², Figs. 9 and 10, is contracted at 90 one end, to form a reduced mouthpiece portion 9, and in this portion are internal flanges 10 and 11 performing the same function as the flanges 1 and 2 in Fig. 2. The larger end of the holder A² is split to form 95 jaws 12, and these jaws are rendered resilient by making openings or recesses 13 at the opposite sides of the holder, leaving the reduced connecting portions 14 at the inner ends of the jaws. These openings 13 also facilitate 100 the gripping of the cigar stub for removing it from the holder. According to Figs. 11 and 12, one of the jaws 12^a may be connected with the body of the holder by a hinge 15, and a spring 16 on this jaw serves to hold the 105 same in normal position, as shown by full

lines, Fig. 12. On this jaw may be provided a pin or barb 17 which penetrates the cigar and more effectively holds the same.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claim.

Having thus described my invention, I claim as new and desire to secure by Letters Patent:

A holder of the class described comprising a tubular body, an internal flange in the body at a point intermediate its ends, and another internal flange at one end of the body and coöperating with the first-mentioned flange to form a nicotin-receiving chamber with central holes at both ends, the portion of the body opposite the end having the flange being shaped into jaws for gripping the article to be smoked, there being spaces between adjacent side edges of the jaws. 20 25

NISHAN M. BOYAJIAN.
